(57) CLAIM

The ornamental design for a billiards showroom fixture, as shown and described.

DESCRIPTION

FIG. 1 is a perspective view of a billiards showroom fixture, showing my new design;

FIG. 2 is a front elevational view, wherein the rear elevational view is substantially identical;

FIG. 3 is a right-hand side elevational view thereof, wherein the left-hand side elevational view is substantially identical; and,

FIG. 4 is a top plan view thereof.
